UNITED STATES PATENT OFFICE.

LEWIS J. BAZZONI, OF SWAMPSMOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

BUTTONING-MACHINE.

1,273,442.

Specification of Letters Patent. Patented July 23, 1918.

Application filed May 22, 1916. Serial No. 99,144.

To all whom it may concern:

Be it known that I, LEWIS J. BAZZONI, a citizen of the United States, residing at Swampscott, in the county of Essex and State of Massachusetts, have invented certain Improvements in Buttoning-Machines, of which the following description, in connection with the accompanying drawings, is a specification, like reference characters on the drawings indicating like parts in the several figures.

This invention relates to buttoning machines, and is herein shown as embodied in a machine particularly adapted for use in the manufacture of boots and shoes for buttoning, in accordance with the usual practice, several of the buttons of the shoe upper prior to the assembling and lasting operations in order to facilitate the proper lasting of the shoe and to insure that the button piece and the buttonhole fly shall be correctly positioned in the finished shoe. It should be understood, however, that the invention, in many of its features and in its broader aspects, is not limited in utility to machines for buttoning shoes nor restricted to the precise embodiment herein illustrated, but is susceptible of various embodiments and applicable to various uses upon different classes of work.

The invention is herein illustrated as embodied in a machine for buttoning a plurality of buttons simultaneously, but it will be apparent from a consideration of the construction and mode of operation of various portions of the illustrative machine that in many of its aspects the invention is not limited to a machine of this particular type.

Important objects of the invention are to provide a machine of simple construction and mode of operation which may be used to perform buttoning operations in a rapid and effective manner, and to provide a machine which may be used with equally effective results upon different lines of work including a wide range of variation in the spacing of the buttons and the buttonholes and in the shape and size of the buttons.

To the above and other ends important features of the invention consist in novel and improved means for relatively positioning a button and a buttonhole fly and for effecting relative movement of the button

and the buttonhole fly to perform a buttoning operation. In the construction shown the button is positioned in edgewise relation to the corresponding buttonhole upon the initial presentation of the work to the machine, and the button is then moved toward the buttonhole fly to cause it to enter the buttonhole in such relation. The illustrated construction comprises a buttoning member which engages the side of the button head to move the button toward the buttonhole and during its continued operation upon the button serves to tip the button substantially into buttoned position.

A further feature of the invention consists in novel buttonhole fly positioning means, including means movable into engagement with the fly to maintain it in the correct position during the buttoning operation. The construction shown comprises presser members movable into position to support the buttonhole fly against pressure in the buttoning operation, and means to insure movement of these members to operative position before the buttoning operation is performed.

The invention provides also, as a further feature, novel button guiding means for facilitating the presentation of work to the machine, this means being arranged to direct the button into its initial position in the machine and being movable subsequently to an inoperative position to avoid interference with other instrumentalities. Preferably, as herein shown, the button guiding means and the buttonhole fly engaging means hereinbefore referred to, are arranged to be operated in sequence to insure that the button guiding means shall be moved to inoperative position before the buttonhole fly engaging means is moved to its operative position.

A further novel and important feature of the invention, as related to means for buttoning a plurality of buttons at each presentation of work to the machine, consists in means for operating in succession buttoning instrumentalities associated respectively with different buttons in such manner as to avoid the buttoning of any two adjacent buttons of the series at the same time. In the illustrative construction the several buttoning instrumentalities are divided into two groups, the members of each group

comprising instrumentalities alternately disposed in the series, and the two groups perform their operations in succession, the members of each group being operated simultaneously. An important advantage of this construction and mode of operation arises from the facility with which the buttons are admitted within the buttonholes by reason of the freedom for yielding movement of the stock at opposite sides of the respective buttonholes, in consequence of which buttons with unusually wide heads may be readily buttoned in a machine constructed in accordance with this feature of the invention.

10 The above and also other features of the invention, residing particularly in novel provision for relative adjusting movement of a plurality of sets of operating instrumentalities for buttoning a plurality of buttons, in the general organization of the machine for the purposes in view, and in various novel details of construction and combination of parts, will now be described with reference to the accompanying drawings and pointed out in the claims.

In the drawings,

Figure 1 is a perspective view of a machine in which the invention is embodied, with a portion of the casing broken away to show the interior construction.

Fig. 2 is a vertical section in a plane extending centrally of the machine from front to back,

Fig. 3 is a perspective view showing, in detached relation, a portion of the operating means for the buttoning members,

Fig. 4 is a perspective view showing, in detached relation, means with which the machine is provided for engaging the buttonhole fly, together with a portion of the mechanism for controlling the operation of the machine.

Fig. 5 shows in greater detail a portion of the mechanism shown in Fig. 4, with the parts in disassembled relation,

Fig. 6 shows, detached, one of several sets of instrumentalities and associated parts with which the machine is provided for use in performing buttoning operations,

Fig. 7 is a plan view of a controlling member for determining the spacing of the several sets of instrumentalities,

Figs. 8 and 9 are views approximately in front elevation of the several sets of instrumentalities, the two figures illustrating respectively different stages in the operation of the machine,

Fig. 10 is a detail view of a portion of the mechanism shown in Figs. 8 and 9,

Figs. 11, 12 and 13 show partly in vertical section and partly in side elevation the mechanism for operating the buttoning members, seen also in Figs. 2 and 3, and illustrate successive stages in the operation of the machine,

Figs. 14 to 18 inclusive show partly in side elevation and partly in vertical section portions of one of the sets of operating instrumentalities and mechanism intimately associated therewith in the control of a button and the buttonhole fly, these figures illustrating successive stages in the operation of the machine upon a piece of work,

Figs. 19, 20 and 21 are perspective views of portions of the mechanism shown in Figs. 16, 17 and 18, illustrating the same successive stages of the operation as said figures, and

Fig. 22 shows the upper end portion of one of the buttoning members.

The operative portions of the machine are supported upon a base casting 2, and the machine, with the exception of a small portion of the mechanism at the front, is normally inclosed in a casing comprising a main portion 4 and a cover 6, the base 2 and the parts supported thereby being readily removable as a unit from the casing. The base 2 supports directly means for imparting movements to the various instrumentalities for operating upon the buttons and the buttonhole fly, and secured to the base 2 also is a frame casting 8 upon which said instrumentalities are mounted, the frame 8 and the parts supported thereby being detachable as a unit from the base 2 to permit the various parts of the machine to be readily inspected or repaired.

Mounted upon the frame 8 are a plurality of sets of instrumentalities, each of which, in the construction shown, comprises means for receiving and positioning a button attached to a button piece, means for guiding the button into the button positioning means, a member for engaging and moving the button, herein termed a buttoning member, and a member constructed and located for engagement in a buttonhole to position the buttonhole relatively to the button. In the machine shown these sets are seven in number in order to adapt the machine for buttoning seven buttons at each presentation of a piece of work to the machine, but the number of the sets may be varied as desired. The central set, as a unit, is stationary with the frame 8, as shown in Fig. 2. The other sets are movable relatively to the central set and to each other to conform to differences in the spacing of the buttons and buttonholes in different pieces of work, and each movable set is carried by a downwardly inclined bar 10 (Fig. 6) forked at its rear end and provided with slots 12 to embrace blocks 14 on a pin 16 which has enlarged ends mounted to turn in bearings 18 on the frame 8. The bar 10 is thus permitted to swing about the axis of the pin 16 and also to move lengthwise relatively to the pin, the front portion of the bar resting upon a bearing portion 19 of the frame. At its front end each bar

110

115

120

125

130

is forked to provide bearings 20 and 22 in which a rod or plunger 24 is movable lengthwise in substantially perpendicular relation to the bar, the frame 8 being constructed to 5 provide similar bearings for the corresponding rod of the central set of instrumentalities, as shown in Fig. 2. Sleaved on each rod 24 and formed with lugs projecting at opposite sides of the bearing 22 to prevent it 10 from moving with the rod, is a member 26 which presents at the front an upwardly projecting plate 28 provided with a slot or opening 30 for the reception of a button when the work is presented to the machine, the 15 member 28 with the slot 30 formed therein thus constituting a fork for engagement under a button head at opposite sides of the shank or eye of the button to position the button for the buttoning operation. Each 20 end fork of the series has within it a curved spring 29 to assist in retaining the end button in position. Each rod 24 is enlarged at its upper end to provide a head 32 (Fig. 22), which in the idle position of the rod lies 25 directly beneath the head of a button positioned in the fork 28 (Fig. 14), and the rod has also a flattened portion 35 on one side (Fig. 22) with which a screw 37 in the member 26 coöperates to prevent any 30 substantial turning movement of the rod. The rod 24 together with the head 32 constitute a buttoning member which is movable upwardly to perform a buttoning operation with respect to the button, as will be 35 hereinafter explained. This member is normally maintained by gravity in its lowermost position determined by the engagement with the bearing 20 of a stop 34 (Fig. 6) on four of the rods 24 or a stop in the form 40 shown at 36 (Fig. 10) on the other three rods. Surrounding the rod between this stop and a loose collar 38 is a spring 40 which insures the quick return of the rod after its upward movement. When the rod is in its 45 lowermost position, however, the spring is fully expanded and the collar 38 is supported loosely on the upper end of the spring. Each of the members 26 is also provided with a finger 42 which projects upwardly at 50 the rear of the head 32 of the buttoning member somewhat farther than the fork 28 for the purpose of engagement in a buttonhole to position the buttonhole relatively to the button, as shown in Fig. 15.

55 Each of the members 26 has depending ears 44 for engagement in a slot 46 formed in a guide plate 48 secured to the frame 8, in order to prevent the member from turning and insure its correct relative location 60 in the adjustment of the bar 10. The slot 46 is curved to approximate the usual curve of the line of buttonholes in a shoe upper and consequently positions the several sets of instrumentalities in accordance with such 65 curve to permit the several buttonholes to be properly positioned by the fingers 42 for the buttoning operation. In order to insure that the several sets of instrumentalities shall be substantially equidistantly spaced in all positions of adjustment, a controller plate 70 75 80 85 90 95 100 105 110 115 120 125 130

50 is pivoted centrally upon the frame 8 over the several bars 10 and is slotted as shown, (Figs. 1 and 7), to receive rolls 52 on the bars 10, the rolls being somewhat loosely received in the slots in order to leave each 75 bar free to move to a small extent independently of the others to conform to possible slight variations in the spacing of the buttons or buttonholes on the same piece of work. The slots in the plate 50 are so formed relatively to the arc of movement of the plate as to cause the plate, when moved, to effect proportional movements of the bars 10 such as to maintain their front ends substantially equidistant from one another and also maintain substantially the same equidistant relation between the central set of instrumentalities and the front ends of the bars 10 on opposite sides thereof. It will be apparent that with this construction adjusting 90 movements of the several sets of instrumentalities with the exception of the central fixed set, may be readily effected by engaging and moving any one of the movable sets along the slot 46, and that any necessary adjustment will ordinarily take place automatically as the buttons are inserted in the forks 28. Since the springs 40, as above explained, are normally expanded and the collars 38 are spaced below the guide plate 48, these 100 collars oppose no resistance through friction to the adjustment of the several sets along the guide plate.

Pivoted on each member 26 is a button guiding device comprising a member 54 formed at the front with projections 56 which, in the normal position of the member 54, constitute an extension of the fork 28, these projections having widely flaring inner edges for guiding the button readily into 110 the fork 28. Each member 54 is provided at the rear with a lug 58 which is positioned in a slot 60 in an operating member 62, the member 62 being curved similarly to the slot 46 to cause the lugs 58 to remain in the slot 60 in all positions of adjustment of the members 26. The operating member 62 is secured to the front end of a carrier 64 which comprises a lever pivoted on a rod 66 on the frame 8 and pivotally connected at 115 its rear end to a rod 68 arranged to be lifted by a suitable treadle, not shown in the drawings. A spring 70 normally depresses the treadle rod 68 and the rear end of the lever 64 and thus positions the members 54 120 as shown in Figs. 2 and 14. By depressing the treadle the operator is enabled to swing the members 54 rearwardly to positions such as indicated in Fig. 15, in order to permit the buttonhole fly to be positioned over the 125 130

forks 28 and to remove the members 54 from the field of action of other instrumentalities the construction and operation of which will now be described.

5 After the buttonhole fly has been positioned on the fingers 42 and before the buttons are moved upwardly toward the buttonholes, the fly is engaged by two presser members 72 and 74 to assist in positioning 10 the fly for the buttoning operation. The member 72 engages the fly adjacent to the fingers 42 to retain the fly on the fingers and prevent it from being pushed upwardly by the buttons, and the member 74 engages the 15 fly close to the forks 28 to hold it against the ends of the forks and prevent it from yielding unduly under the pressure of the buttons, the operative positions of these members being indicated in Figs. 16, 17 and 20 18. In the construction shown the member 20 72 moves to an operative position in front of the fingers 42, but it will be understood that the member may be arranged to engage the buttonhole fly at the rear of these fingers 25 if desired. Both members 72 and 74 are curved similarly to the slot 46. The member 72 is secured to a lever 76 which is fulcrumed on a rock shaft 78 mounted on the frame 8, and the lever 76 is operated by a 30 rocker 80 secured to a rock shaft 82 which is pivoted on the frame, the rocker having a cam slot 84 to receive a rod 86 on the rear end of the lever 76. Movement of the rocker in a counter-clockwise direction, (Fig. 2), 35 thus serves to move the member 72 from the position indicated in Fig. 2 to that indicated in Figs. 4 and 16.

The member 74 is pivoted by means of a rod 88 on an upwardly projecting arm 90 40 of the rocker 80. Secured to the rock shaft 78 are two arms 92 each having a cam slot 94 to receive a roll 96 on the member 74 and another slot 98 curved in substantially concentric relation to the axis of the shaft 82 45 to receive the adjacent end of a rod 100 which is mounted on eccentric 102 adjustably rotatable in bearings in the arm 90. It will be apparent that with this construction movement of the rocker 80 to carry the member 72 to operative position will first serve 50 to carry the member 74 bodily forward out of the path of movement of the member 72 and then by reason of the engagement of the roll 96 in the cam slot 94 to impart to the member 74 a combined forward movement 55 and downward swinging movement about the axis 88 to bring the member to the operative position indicated in Fig. 16, the member 72 being moved simultaneously to 60 the operative position indicated in said figure. The arms 92, although free to turn about the axis of the shaft 78, are normally restrained from any substantial movement of this character through the engagement 65 of the rod 100 in the slots 98, the rod 100

thus determining the position of the arms 92 and consequently the extent of depression of the clamp member 74. By adjusting the eccentrics 102 in their bearings the position of the arms 92 may be changed to cause the 70 member 74 to bear upon the stock with varying pressure.

Mounted in bearings in the base 2 is a power shaft 104 to which movement is imparted from a belt pulley 106 through a 75 suitable clutch, such as a Horton clutch, of which the controlling member is seen at 108 (Fig. 1), the member 108 being held normally in clutch releasing position by means of a stop pin 110 which is yieldably mounted 80 in one arm of a lever 112 pivoted on the base 2 at 114. The lever 112 carries also a catch 116 for engagement with teeth on a clutch sleeve 118 to prevent backlash when movement of the member 108 is 85 stopped by the pin 110. The lever 112 is operated to trip the clutch by means of a suitable treadle, not shown in the drawings, this treadle being connected to a treadle rod 120 which is pivoted to the lower end 90 of a bar 122 from the upper end of which a rod 124 projects through an opening in the frame 8 and is surrounded by a spring 126 which bears upwardly against a nut on the upper end of the rod to hold the bar 95 122 normally in its uppermost position. The bar 122 carries a clutch tripping pin 128 for engagement with a latch 130 on the lower end of the lever 112, the latch being pivoted to the lever and operated upon by 100 a spring 132 to cause its front end to be normally depressed as far as permitted by the engagement of its rear end with the lever 112. In the downward movement of the bar 122 the pin 128 engages the latch 105 130 and swings the lever 112 to trip the clutch and cause power to be transmitted to the shaft 104, and as the bar 122 continues its downward movement the pin 128 110 passes below the latch 130 and permits the 112 lever to return to clutch releasing position so as to disconnect the clutch at the end of a single revolution of the power shaft. When the treadle is released the bar 122 is pulled upward by the spring 115 126, the pin 128 tripping the latch 130 during this movement. The pin 128 is flattened on one side, as shown in Fig. 4, in order to provide a well defined edge for co-operation with the end of the latch 130 120 to insure tripping of the clutch at the precise point required, and the pin may be turned and secured in different positions of adjustment in order to vary the time in the downward movement of the bar 122 when 125 the clutch is tripped.

The power shaft 104 carries a contour cam 134 and the clamp operating rocker 80 carries a roll 136 for engagement with the periphery of this cam, the rocker being op- 130

erated upon by a spring 138 to maintain the roll normally in engagement with the cam. Movement of the rocker 80 to carry the members 72 and 74 to operative position, however, is not effected by the cam 134 but by the starting treadle through the downward movement of the bar 122. To this end a lever 140 is pivoted on a lug 142 formed on the frame 8, the lower arm of the lever carrying a roll 144 for engagement in a recess 146 in the bar 122 and the upper arm of the lever engaging a roll 148 mounted on an arm 150 on the rock shaft 82 to which the rocker 80 is secured. When the machine is idle, as shown in Fig. 1, the roll 144 is free to engage in the bottom of the recess 146 in the bar 122, thus leaving the connections 140, 150 free to permit the spring 138 to position the rocker 80 as shown in Fig. 2 with the roll 136 on the low concentric portion of the cam 134. When the treadle rod 120 is depressed to start the machine, the first operation of the bar 122, before the clutch is tripped, is to swing the lever 140 through the engagement of a cam face 152 (Fig. 1) on the bar with the roll 144, and thus rock the shaft 82 to move the members 72 and 74 to operative position. The roll 136 during this movement of the rocker 80 is lifted from the cam 134. It is only after the members 72 and 74 have thus assumed their operative positions that the clutch is tripped, through the action of the pin 128 on the latch 130, to operate the machine. In Fig. 4 the parts are shown in the positions that they assume after the members 72 and 74 have been operated and before the bar 122 has been moved downward far enough to trip the clutch. During the further downward movement of the bar a face 154 on the bar engages the roll 144 to hold the lever 140 in the position to which it has been moved. When the machine is started through the tripping of the clutch, during the high portion of the cam 134 moves under the roll 136 to support the rocker 80 firmly in the position to which it has been moved by the treadle, thus insuring that the button hole fly shall be firmly held against the pressure of the buttons in the buttoning operation. After the buttoning operation has been performed the rocker is released by the cam to permit the members 72 and 74 to return to their idle positions as soon as the operator releases the treadle. It will be apparent that the machine will stop at the end of a single revolution of the power shaft notwithstanding the fact that the operator may keep the treadle depressed until after the cycle of movements has been completed.

It will be readily understood that the button guide members 54 should be swung backward to their idle positions before the members 72 and 74 have been moved into

position to engage the buttonhole fly, in order to avoid interference between the members 54 and the buttonhole fly engaging members. In order to insure this operation a stop 156 is secured to the lever 64 in position to engage a projection 158 at the rear end of the rocker 80 when the various parts are in starting position. The ends of the stop 156 and the projection 158 are interlocked in such relation to the respective axes of the rocker 80 and the lever 64 that movement of the starting treadle to operate the members 72 and 74 and start the machine is positively prevented until such time as the treadle rod 68 has been operated to swing the guide members 54 to their idle positions.

By reference to Figs. 8 and 9 it will be seen that in the construction shown all the buttoning members are not moved upward simultaneously to perform their buttoning operations, but only alternate members of the series, thus facilitating the movement of the buttons through the button-holes and avoiding undue strain upon the stock, particularly in the case of buttons having comparatively wide heads. In the illustrative machine the buttoning members numbered 2, 4 and 6, counting from either side of Fig. 8 or Fig. 9, which will be termed for convenience the first group, are operated first, and after they have performed their buttoning operations the other four buttoning members, comprising the second group, are operated. Each of the stops 36 hereinbefore referred to extends downwardly and under the end of the rod 24, as shown in Fig. 10, these rods in the case of the first group of buttoning members being relatively short. Each stop 36 thus presents a lower end portion 160 extending to the front of the series of rods 24 and positioned over an operating bar 162 which is curved similarly to the slot 46 and is carried by the front arm of a lever 164 (Fig. 3). The lever 164 is fulcrumed on a shaft 166 supported by the base 2 and on its rear arm carries a roll 168 which engages in a groove 170 in a path cam 172. At the rear of the bar 162 is a similarly curved bar 174 which underlies the ends of the four rods 24 of the second group and is carried by the front arm of a lever 176 also fulcrumed on the shaft 166, this lever carrying at its rear end a roll 178 positioned in the cam groove 170. By reference to Figs. 11, 12 and 13 it will be seen that the lever 164 is first operated by the cam 170 to raise the bar 162 to the position shown in Fig. 9 and operate the first group of buttoning members, after which the cam operates the lever 176, while holding the lever 164 at the limit of its operative movement, to cause the buttoning members of the second group to perform their operation. Both rolls 168 and 178 are mounted on eccentric 130

studs, as shown by dotted lines, to permit them to be adjusted in a well known manner to vary the limits of movement of the respective levers.

5 Pivoted on lugs 180 on the base 2 is a brake arm 182 which carries a brake shoe 184 in position to engage the periphery of the cam 134 when the shaft 104 has nearly completed a rotation. A spring 186 operating on the arm 182 renders the brake shoe 184 yieldingly effective on the cam to assist in stopping the shaft in the required position as soon as the clutch is released.

In the use of the machine, with the various parts of the mechanism in their idle positions and the buttonhole fly engaging members 72 and 74 upraised and retracted as shown in Figs. 1 and 2, the operator first positions a button piece such, for example, 15 as that part of the upper of a button shoe to which the buttons are attached, in the machine by inserting several buttons in the corresponding forks 28 which are inclined forwardly from the vertical for the convenient reception of the buttons. The full 20 number of buttons upon which the machine is adapted to operate may be buttoned, or less than the full number, as preferred. The position of the work at this stage of the 25 operations is illustrated in Fig. 14 in which A indicates the button piece and B the button. The auxiliary forks 56 assist in guiding the buttons into the forks 28, and pressure of the buttons on one side or the other 30 of the forks 56 also serves to effect any required adjustment of the several sets of instrumentalities through movement of the bars 10 as determined by the controlling member 50. The buttons having been thus 35 positioned, the operator depresses with one foot that treadle which operates the rod 68, and through the connections described swings the members 54 rearwardly to carry the auxiliary forks 56 to their idle positions, as shown in Fig. 15, keeping this 40 treadle depressed continuously thereafter until the machine has completed its operation. The buttonhole fly C is next positioned as indicated in Fig. 15 with the 45 fingers 42 engaging in the buttonholes to position them over the respective buttons with their lengthwise dimensions in substantially perpendicular relation to the planes of the button heads in the forks 28— 50 i. e., to planes lying at right angles to the eyes or shanks of the buttons. After the work has been thus arranged, the operator depresses the other treadle with which the rod 120 is connected, the operation of this 55 treadle being permitted by reason of the fact that the stop 156 has been lifted out of the path of the projection 158 on the rocker 80. The first operation in the downward movement of the rod 120, as hereinbefore explained, is to move the members 72 and 74

to their operative positions with reference to the buttonhole fly C, as shown in Fig. 16. The continued downward movement of the treadle rod and the bar 122 serves to trip the clutch and cause the shaft 104 to be 70 driven by the pulley 106.

The first operation in the rotation of the shaft 104 is to carry the cam 134 under the cam roll 136 and thus support the rocker 80 against any pressure tending to raise the 75 members 72 and 74 in the buttoning operation. In the continued movement of the shaft the cam 172 next operates the lever 164 (Fig. 12) to raise the bar 162 and thus through engagement of the bar with the 80 lower ends 160 of the members 36 to raise the three rods 24 of the first group of buttoning members, and push through the corresponding buttonholes the three buttons engaged by the heads 32 on these rods. Immediately after the completion of this operation and while the three rods of the first group are held in their uppermost position, the lever 176 is operated by the cam 172 to raise the bar 174, as shown in Fig. 13, and thus through the engagement of this bar with the four rods 24 of the second group to cause these rods to perform their buttoning operations and complete the buttoning of the seven buttons. The several parts are 95 then returned to their starting positions by reason of reverse movements of the levers 164 and 176 and movement of the high portion of the cam 134 from beneath the roll 136, the operator having released or immediately releasing the starting treadle to permit the members 72 and 74 to be withdrawn from the work. At the end of a complete rotation of the shaft 104 the clutch is released and the shaft stopped through 100 the action of the brake shoe 184 on the cam 134. The stopping of the shaft may be substantially instantaneous for the reason that the parts that rotate with the shaft are not of such construction as to acquire much momentum. By a simple upward movement the 105 work may then be removed from the machine, and upon the release of the treadle rod 68 the auxiliary forks 56 are returned to 110 their operative positions.

Figs. 17 and 18, and the corresponding Figs. 20 and 21 illustrate the movement of a button under the impulse of the buttoning member. It will be seen that the fork 28 provides a guideway for the button in which the button is presented in edgewise relation to the buttonhole and that as the rod 24 is moved upward with its head 32 in engagement with the side of the button head the button is moved along this guideway until it 120 encounters the buttonhole fly. The head 32 presents an end face slightly curved to conform to the curve of the side of the button head and sloping also at an acute angle to the fork 28 in order to prevent the button 125 130

from tipping prematurely during its upward movement. After the button engages the buttonhole fly it is still moved upward in substantially the same relation to the fork 28 until its leading edge has entered the buttonhole. At this stage the ends of the two side portions of the fork 28 are substantially in alignment with the center of the lower face of the button head, and by reason 10 of the resistance of the button piece transmitted to the button through the attaching stitches the button starts to turn, under the impulse of the rod 24, substantially about the end of the fork 28 as a center. Continued movement of the rod 24 then turns or tips the button, until the button assumes a substantially upright buttoned position with reference to the buttonhole fly. During the final stage of the operative movement of the 20 rod 24 engagement of the shank portion of the button with the side of the head 32 tends to oppose the tipping movement of the button about the end of the fork 28, thus causing the button to be lifted bodily, even after 25 the button has assumed a substantially upright buttoned position relatively to the buttonhole fly, in such manner as to insure that the button head shall clear the buttonhole fly at the edges of the buttonhole. Such 30 clearance is further insured by movement of the leading edge of the button head over the edge of the buttonhole fly engaging member 74 and by continued movement of the rod 24 to a position in which its head 32 projects slightly through the buttonhole, as 35 shown in Fig. 18, and thus spaces the button head from the edges of the buttonhole. It will be apparent that tipping movement of the button is not entirely prevented by the 40 engagement of the button shank with the head 32 and that the button head remains free to adjust itself in accordance with changes in conditions during the continued operation of the buttoning member.

Having described the invention, what I claim as new and desire to secure by Letters Patent of the United States is:

1. A buttoning machine having, in combination, button positioning means constructed 50 to provide a guideway for a button, means for positioning a buttonhole fly with portions of the fly at opposite sides of a buttonhole lying in a plane transverse to the path of movement of the button along said guideway, and means for moving the button along the guideway and into said buttonhole.

2. A buttoning machine having, in combination, button positioning means constructed to provide a guideway for a button, means 60 for positioning a buttonhole fly with a portion of the fly in which a buttonhole is located lying in a plane transverse to the path of movement of the button along said guideway, and means for pushing the button along the guideway by engagement with the

button head to cause the button to enter the buttonhole.

3. A buttoning machine having, in combination, button positioning means constructed to provide a guideway for a button, means 70 for positioning a buttonhole fly with a buttonhole extending transversely across the end of said guideway in position to receive the button, and means for moving the button along the guideway and into the buttonhole. 75

4. A buttoning machine having, in combination, button positioning means constructed to provide a guideway for a button, means for positioning a buttonhole fly with a buttonhole extending lengthwise in transverse relation to the plane of the button head in said positioning means and in position to receive the button, and means for moving the button along said guideway and into the 80 buttonhole. 85

5. A buttoning machine having, in combination, button positioning means provided with an open-ended recess for the reception of a button, means for positioning a buttonhole fly with a buttonhole extending across the open end of said recess in position to receive the button, and means for engaging the button in said recess and moving it into the 90 buttonhole. 95

6. A buttoning machine having, in combination, a fork constructed and arranged to receive a button attached to a button piece, means for engaging the button in said fork and moving the button reversely toward the 100 end of the fork, and means for positioning a buttonhole fly with a buttonhole in position to be entered by the button at the end of said fork.

7. A buttoning machine having, in combination, button positioning means provided with an upwardly directed opening to receive a button, means for positioning a buttonhole fly with a buttonhole extending across the end of the opening, a button engaging member, and means for operating said member to move the button toward the end of the opening and into the buttonhole. 105 110

8. A buttoning machine having, in combination, means for relatively positioning a button and a buttonhole fly when the work is initially presented to the machine with a portion of the fly in which a buttonhole is located extending in transverse relation to the plane of the button head, and means for 115 effecting relative movement of the button and the buttonhole fly in said relation to cause the button to enter said buttonhole. 120

9. A buttoning machine having, in combination, means for relatively positioning a 125 button and a buttonhole fly with the plane of the button head transverse to the lengthwise dimension of a button hole in said fly, and means for effecting a relative movement of the button and the buttonhole fly to cause 130

the button to enter the buttonhole in said relation.

10. A buttoning machine having, in combination, means for relatively positioning a button and a buttonhole fly with the button in edgewise relation to a buttonhole when the work is initially presented to the machine, and means for performing a buttoning operation with respect to said button and buttonhole.

11. A buttoning machine having, in combination, means for relatively positioning a button and a buttonhole fly, a member for engaging the side of the button head remote from said fly, and means for operating said member to push the button into a buttonhole in said fly.

12. A buttoning machine having, in combination, means for relatively positioning a button and a buttonhole fly with the plane of the button head transverse to the lengthwise dimension of a buttonhole in said fly, and means for effecting relative movement of the button and the buttonhole fly to cause the button to enter the buttonhole and to be tipped to an upright buttoned position with reference to said fly.

13. A buttoning machine having, in combination, means for relatively positioning a button and a buttonhole fly with the plane of the button head in substantially perpendicular relation to the plane of a portion of said fly in which a buttonhole is located, and means for effecting relative movement of the button and the buttonhole fly to cause the button to enter the buttonhole in said relation and then to be tipped to an upright buttoned position with reference to said fly.

14. A buttoning machine having, in combination, means for relatively positioning a button and a buttonhole fly with the button in edgewise relation to a buttonhole when the work is initially presented to the machine, and means for effecting relative movement of the button and the buttonhole fly to cause the button to enter the buttonhole in said edgewise relation and then to be tipped to buttoned position.

15. A buttoning machine having, in combination, means for relatively positioning a button and a buttonhole fly with the button in edgewise relation to a buttonhole, a buttoning member, and means for operating said member to push the button into the buttonhole, said member being constructed and arranged for coöperation with said positioning means to tip the button into buttoned position.

16. A buttoning machine having, in combination, button positioning means constructed to provide a guideway for a button, buttonhole fly engaging means, and a member for engaging the side of the button head to push the button along said guideway

and into a buttonhole, said member being 65 constructed to prevent the button from tipping relatively to the guideway prior to its entrance into the buttonhole.

17. A buttoning machine having, in combination, button positioning means constructed to provide a guideway for a button, buttonhole fly engaging means, and a member for engaging the side of the button head to push the button along said guideway and 70 into a buttonhole, said member having a 75 button engaging face inclined to the guideway to prevent the button from tipping prior to its entrance into the buttonhole.

18. A buttoning machine having, in combination, button positioning means provided 80 with an opening to receive a button, means for positioning a buttonhole fly with a buttonhole at the end of said opening in position to be entered by the button, and buttoning means constructed and arranged to move 85 the button toward the end of said opening and into the buttonhole and to tip the button about said button positioning means into buttoned position.

19. A buttoning machine having, in combination, a button receiving fork arranged to position a button for a buttoning operation, means for positioning a buttonhole fly with a buttonhole at the end of said fork in position to be entered by the button, and 95 buttoning means constructed to push the button toward the end of the fork and into the buttonhole and to tip the button about the end of the fork into buttoned position.

20. A buttoning machine having, in combination, button positioning means constructed to provide an opening for the reception of the shank of a button, means for positioning a buttonhole fly with a buttonhole at the end of said opening in position 100 to be entered by the button, a member for engaging the button head, and means for operating said member to push the button toward the end of said opening and into the buttonhole and to tip the button in the buttonhole to cause the shank of the button to engage said member, said operating means 105 being constructed to continue the movement of said member after the shank of the button has thus engaged to impart an additional bodily movement to the button.

21. A buttoning machine having, in combination, means for relatively positioning a button and a buttonhole fly for a buttoning operation, a buttoning member movable in engagement with the side of the button head to push the button into a buttonhole and also to tip the button in the buttonhole to cause the member to engage under the edge of the button head to complete the buttoning operation, and means for engaging under the button head on the opposite side of the button from said member and between the

button head and the buttonhole fly to coöperate with said member in completing the buttoning operation.

22. A buttoning machine having, in combination, button positioning means constructed to provide an opening for the reception of the shank of a button, means for positioning a buttonhole fly with a button-hole at the end of said opening in position to be entered by the button, a member for engaging the button head, and means for operating said member in engagement with the side of the button head to push the button toward the end of said opening and into the buttonhole and then to tip the button to cause the member to engage under the edge of the button head, said buttonhole fly positioning means comprising a member constructed to engage under the leading edge 15 of the button head to coöperate with said first named member in completing the buttoning operation.

23. A buttoning machine having, in combination, a plurality of devices coöperating to perform a buttoning operation with respect to a button and a buttonhole, and means for relatively operating said devices to perform a buttoning operation, said operating means being constructed and arranged to cause bodily movement of the button in a direction transverse to the plane of the buttonhole fly with the button in a substantially upright position relatively to said fly to insure that the button head shall clear 35 the fly at the edges of the buttonhole.

24. A buttoning machine having, in combination, a plurality of devices coöperating to perform a buttoning operation with respect to a button and a buttonhole, and means for relatively operating said devices to perform a buttoning operation, said operating means being constructed and arranged to cause the button to be lifted bodily relatively to the buttonhole fly by 45 engagement under the button head in the final stage of the buttoning operation, with the button in a substantially upright position relatively to said fly, to insure that the button head shall clear the fly at the edges 50 of the buttonhole.

25. A buttoning machine having, in combination, a plurality of devices coöperating to perform a buttoning operation with respect to a button and a buttonhole including means for engaging the buttonhole fly on 55 opposite sides of the button, and means for relatively operating said devices to perform a buttoning operation, said operating means being constructed and arranged to cause the 60 button to be moved bodily in a direction transverse to the plane of the buttonhole fly and in a substantially upright position relatively to said fly in the final stage of the buttoning operation to insure that the button

head shall clear the fly at the edges of the 65 buttonhole.

26. A buttoning machine having, in combination, a plurality of devices coöperating to perform a buttoning operation with respect to a button and a buttonhole comprising means for engaging the buttonhole fly on the opposite side from the button and means for supporting the button from beneath while leaving the button free to tip relatively to the supporting means, and means for relatively operating said devices to perform a buttoning operation, said devices comprising also means for engaging the button under the edge of the button head between the head and the buttonhole fly to insure that the button head shall clear the fly at the edge of the buttonhole in the final stage of the buttoning operation.

27. In a buttoning machine, buttoning means, button positioning means provided with an opening to receive a button in operative relation to said buttoning means when the work is initially presented to the machine, and buttonhole fly positioning means comprising a member constructed and arranged for engagement in a buttonhole to position the buttonhole over the button in said opening.

28. In a buttoning machine, button positioning means constructed to provide a guideway for a button, and buttonhole fly positioning means comprising a member extending lengthwise of said guideway and constructed to engage in a buttonhole when the work is initially presented to the machine to position the buttonhole fly in transverse relation to said guideway.

29. In a buttoning machine, an upwardly directed button receiving fork, and a member at the rear of said fork constructed to engage in a buttonhole when the work is initially presented to the machine to position a buttonhole fly across the end of said fork.

30. In a buttoning machine, button positioning means provided with an opening to receive a button in position for a buttoning operation, means for positioning a buttonhole fly with that portion of the fly which extends about the buttonhole lying in a plane substantially perpendicular to the plane of the button head, and means movable into engagement with the buttonhole fly adjacent to said opening to prevent displacement of said fly during the buttoning operation.

31. In a buttoning machine, button positioning means provided with an opening to receive a button in position for a buttoning operation, a member constructed and arranged to engage in a buttonhole in a buttonhole fly during the buttoning operation to position the buttonhole relatively to the button, and means movable into engagement

with that portion of the buttonhole fly which is adjacent to said member to prevent displacement of the fly relatively to said member during the buttoning operation.

5 32. A buttoning machine having, in combination, button positioning means constructed to provide a guideway for a button, a button engaging member movable along said guideway to perform a buttoning operation with respect to said button, and a member positioned at the opposite side of said button engaging member from the guideway for engagement in a buttonhole to position a buttonhole fly transversely of 10 said guideway.

15 33. A buttoning machine having, in combination, button positioning means constructed to provide a guideway for a button, means for positioning a buttonhole fly 20 with portions of the fly at the opposite sides of a buttonhole lying in a plane transverse to the direction of movement of the button along said guideway, and means for moving the button along the guideway to cause the 25 button to enter the buttonhole, said buttonhole fly positioning means being constructed and arranged to support the fly against pressure of the button.

30 34. A buttoning machine having, in combination, buttonhole fly engaging means, buttoning means, and mechanism for operating the buttoning means to force a button into a buttonhole in said fly, said buttonhole fly engaging means being constructed 35 and arranged to engage the fly on opposite sides of the path of movement of the button to support the fly against pressure of the button.

40 35. A buttoning machine having, in combination, buttonhole fly engaging means, buttoning means, and mechanism for operating the buttoning means to cause a button to enter a buttonhole in said fly, said buttonhole fly engaging means being constructed 45 and arranged to engage the fly adjacent to opposite ends of the buttonhole to support the fly against pressure in the buttoning operation.

50 36. A buttoning machine having, in combination, means for moving a button to perform a buttoning operation, a member constructed and arranged to engage in one end of a buttonhole in a buttonhole fly to position the buttonhole in the path of movement 55 of the button, and means for engaging the buttonhole fly adjacent to said member and adjacent to the opposite end of the buttonhole to support the fly against pressure in the buttoning operation.

60 37. A buttoning machine having, in combination, a button positioning fork, means for engaging a button in said fork and moving the button toward the end of the fork to perform a buttoning operation, a member 65 arranged to engage in a buttonhole in a but-

tonhole fly to position the buttonhole at the end of said fork, and means for engaging the buttonhole fly adjacent to said member and also adjacent to the fork to retain the fly on said member and support the fly 70 against pressure of the button.

38. A buttoning machine having, in combination, buttoning means movable to perform a buttoning operation, and means for engaging a buttonhole fly to support it 75 against pressure in the buttoning operation, said buttonhole fly engaging means comprising members movable to engage the fly respectively adjacent to opposite ends of a buttonhole, one of said members being 80 movable lengthwise of the buttonhole to facilitate the presentation of a button to said buttoning means when said member is withdrawn.

39. A buttoning machine having, in combination, buttoning means movable to perform a buttoning operation, buttonhole fly engaging means, and manually operated means for moving said buttonhole fly engaging means to operative position prior to 90 the operative movement of said buttoning means.

40. A buttoning machine having, in combination, buttoning means movable to perform a buttoning operation, buttonhole fly 95 engaging means, manually operated means for initiating the operation of said buttoning means, and means connecting said manually operated means to the buttonhole fly engaging means for moving said last named 100 means to operative position prior to the operation of the buttoning means.

41. A buttoning machine having, in combination, buttoning means movable to force a button into a buttonhole in a buttonhole 105 fly, a clutch for connecting said means to a source of power, manual means for operating said clutch, buttonhole fly engaging means movable into position to support the fly against pressure in the buttoning operation, and means connecting said manual 110 means to the buttonhole fly engaging means to cause said last named means to be moved manually to operative position prior to the operation of the clutch.

42. A buttoning machine having, in combination, buttoning means movable to force a button into a buttonhole, buttonhole fly engaging means for supporting the fly against pressure in the buttoning operation, 120 manually operated means for moving said buttonhole fly engaging means to operative position, a power shaft, connections between the power shaft and the buttoning means for operating said means, and means 125 connected with said manually operated means for initiating the operation of the power shaft.

43. A buttoning machine having, in combination, buttoning means, buttonhole fly 130

engaging means, manually operated means for moving said buttonhole fly engaging means to operative position, and power operated means for maintaining the buttonhole fly engaging means in operative position during the buttoning operation.

44. A buttoning machine having, in combination, buttoning means movable to force a button into a buttonhole, a power shaft, connections between the power shaft and the buttoning means for operating said means, buttonhole fly engaging means for supporting the fly against pressure in the buttoning operation, manually operated means for moving said buttonhole fly engaging means to operative position and for initiating the operative movement of the power shaft, and a cam on said shaft movable into position to maintain the buttonhole fly engaging means in operative position during the buttoning operation.

45. A buttoning machine having, in combination, button positioning means arranged to receive a button when the work is initially presented to the machine, buttoning means for performing a buttoning operation with respect to said button, means for guiding the button into said button positioning means, and means for moving the button guiding means relatively to the button positioning means to an inoperative position prior to the operation of the buttoning means.

46. A buttoning machine having, in combination, button positioning means having an opening for the reception of a button, buttoning means for performing a buttoning operation with respect to a button in said opening, means for guiding a button into said opening, and means for moving the button guiding means to an inoperative position prior to the operation of the buttoning means.

47. A buttoning machine having, in combination, button positioning means arranged to receive a button when the work is initially presented to the machine, means for guiding a button into said button positioning means, means for positioning a buttonhole fly over the button positioning means, and means for withdrawing said button guiding means to permit the buttonhole fly to be thus positioned.

48. A buttoning machine having, in combination, button positioning means arranged to receive a button when the work is initially presented to the machine, means for guiding the button into said button positioning means, means for withdrawing the button guiding means from operative position, buttonhole fly engaging means movable into operative relation to the fly, and means for preventing such movement of the buttonhole fly engaging means prior to the withdrawal of the button guiding means.

49. A buttoning machine having, in combination, button positioning means arranged to receive a button when the work is initially presented to the machine, means for guiding a button into said button positioning means, buttoning means for performing a buttoning operation with respect to said button, buttonhole fly engaging means movable into position to support the fly against pressure in the buttoning operation, manually operated means for moving said buttonhole fly engaging means to operative position, means for withdrawing the button guiding means from operative position, and means for locking said manually operated means against movement prior to the withdrawal of said guiding means.

50. In a buttoning machine, the combination of button positioning means, and button guiding means movable relatively to the button positioning means into or out of position to direct a button into said button positioning means.

51. In a buttoning machine, button positioning means having an opening for the reception of a button, and button guiding means having a wider button receiving opening and movable relatively to the button positioning means into or out of position to direct a button into the opening in said positioning means.

52. In a buttoning machine, a button receiving fork, and a button guiding device constructed to form an extension of said fork when in operative position and movable to an inoperative position with reference to the fork.

53. In a buttoning machine, a button receiving fork, and a button guiding device constructed to form an extension of said fork and pivoted to swing either into or out of operative position with reference to the fork.

54. A buttoning machine having, in combination, a plurality of buttoning instrumentalities for buttoning respectively different buttons of a series, and means for operating different groups of said instrumentalities in succession to button first a group of buttons comprising alternate buttons of the series and then to button the remaining buttons.

55. A buttoning machine having, in combination, a plurality of buttoning instrumentalities for buttoning respectively different buttons of a series, and means for operating said instrumentalities in such order as to button a plurality of the buttons simultaneously and adjacent buttons of the series successively.

56. A buttoning machine having, in combination, a plurality of buttoning instrumentalities for buttoning respectively different buttons of a series, and means for operating a plurality of said instrumentalities

simultaneously to button a group of buttons comprising alternate buttons of the series and for then operating the remainder of said instrumentalities simultaneously to button 5 the remaining group of alternate buttons.

57. A buttoning machine having, in combination, means for relatively positioning a buttonhole fly and a plurality of buttons to permit buttoning operations to be performed with respect to the buttons, buttoning members movable to force the respective buttons through the corresponding buttonholes in said fly, and means for operating different groups of said members in succession to button first a group of buttons comprising alternate buttons of the series and then to button the remaining buttons.

58. A buttoning machine having, in combination, means for relatively positioning a buttonhole fly and a plurality of buttons to permit buttoning operations to be performed with respect to the buttons, and means for performing the buttoning operations in such order as to button a plurality 25 of the buttons simultaneously and adjacent buttons of the series successively.

59. A buttoning machine having, in combination, means for relatively positioning a buttonhole fly and a plurality of buttons to permit buttoning operations to be performed with respect to the buttons, a plurality of buttoning instrumentalities arranged respectively for buttoning the different buttons, and means for operating different groups of 35 said instrumentalities in succession.

60. A buttoning machine having, in combination, means for relatively positioning a buttonhole fly and a plurality of buttons to permit buttoning operations to be performed with respect to the buttons, a plurality of buttoning instrumentalities arranged respectively for buttoning the different buttons, a pair of members arranged respectively to operate different groups of 45 said instrumentalities, and means for operating said members respectively at different times.

61. A buttoning machine having, in combination, means for relatively positioning a buttonhole fly and a plurality of buttons to permit buttoning operations to be performed with respect to the buttons, buttoning members movable to force the respective buttons into the corresponding buttonholes, a pair 55 of levers provided respectively with means for operating different buttoning members, and means for operating said levers in succession.

62. In a buttoning machine, a plurality of 60 sets of operating instrumentalities for performing buttoning operations respectively upon a plurality of buttons, the several sets being relatively adjustable to conform to differences in spacing of the buttons on dif-

ferent pieces of work, and means for controlling the relative adjustment of the several sets to maintain them in substantially equidistant relation while permitting such adjustment of the several sets to be effected through movement of one or more of the 70 sets.

63. In a buttoning machine, a plurality of button receiving devices arranged to receive a plurality of buttons when the work is initially presented to the machine, said 75 devices being free to be moved relatively by engagement with the buttons to conform to differences in the spacing of the buttons on different pieces of work.

64. In a buttoning machine, a plurality of button receiving devices arranged to receive a plurality of buttons when the work is initially presented to the machine, said 80 devices being free to be moved relatively by engagement with the buttons to conform to differences in the spacing of the buttons on different pieces of work, and means for controlling the relative movement of the several sets to maintain them in substantially equidistant relation.

65. In a buttoning machine, a plurality of sets of operating instrumentalities for performing buttoning operations respectively upon a plurality of buttons, the several sets being relatively adjustable to conform to 95 differences in spacing of the buttons on different pieces of work, and means for controlling the relative adjustment of the several sets to maintain them in substantially equidistant relation, the controlling means being constructed to permit limited independent relative movements of the different sets.

66. In a buttoning machine, a plurality of sets of operating instrumentalities for performing buttoning operations respectively upon a plurality of buttons, the central set being stationary and the other sets adjustable relatively to each other and to the central set to conform to differences in spacing 100 of the buttons on different pieces of work, and means for controlling the relative adjustment of the several sets comprising a pivoted controlling member having pin and slot connections with the adjustable sets 115 constructed to maintain the several sets in substantially equidistant relation.

67. In a buttoning machine, a plurality of sets of operating instrumentalities for performing buttoning operations respectively upon a plurality of buttons, the central set being stationary and the other sets adjustable relatively to each other and to the central set to conform to differences in spacing 120 of the buttons on different pieces of work, each adjustable set comprising a bar mounted for both swinging movement and lengthwise movement, and means for controlling 125

movement of the several bars comprising guiding means curved to approximate the curve of a series of buttonholes.

68. In a buttoning machine, a plurality of sets of instrumentalities for relatively positioning a plurality of buttons and a buttonhole fly, each set including means to enter and position a buttonhole, the several sets being relatively adjustable to conform to differences in spacing of the buttons and buttonholes on different pieces of work, and means for controlling the adjustment of the sets comprising guiding means curved to approximate the curve of a series of buttonholes.

69. In a buttoning machine, a plurality of sets of operating instrumentalities for performing buttoning operations with respect to a plurality of buttons and comprising button and buttonhole fly positioning means, the several sets being arranged in a curve corresponding approximately to the curve of a series of buttonholes, and a buttonhole fly engaging member movable into or out of operative relation to the buttonhole fly, said member comprising a bar curved similarly to the curve in which the several sets are arranged.

70. A buttoning machine having, in combination, means for relatively positioning a plurality of buttons and a buttonhole fly to permit a plurality of buttoning operations to be performed substantially simultaneously, and buttonhole fly engaging means comprising a bar arranged to engage the fly along the series of buttonholes to assist in positioning the buttonhole fly during the buttoning operations.

71. A buttoning machine having, in combination, means for relatively positioning a plurality of buttons and a buttonhole fly to permit a plurality of buttoning operations to be performed substantially simultaneously, and buttonhole fly engaging means comprising a pair of bars movable to engage the fly substantially at opposite sides of the series of buttonholes to assist in positioning the buttonhole fly during the buttoning operations.

72. A buttoning machine having, in combination, button positioning means provided with a plurality of openings for the reception of buttons attached to a button piece when the work is initially presented to the machine, means for positioning a buttonhole fly with the buttonholes over the corresponding buttons in said openings, means for performing buttoning operations with respect to said buttons and buttonholes, and a member movable into engagement with the buttonhole fly to prevent displacement of the fly with reference to the several buttons during the buttoning operations.

73. A buttoning machine having, in com-

bination, button positioning means provided with upwardly and forwardly directed openings for the reception of a plurality of buttons attached to a button piece, means for positioning a buttonhole fly with buttonholes in position to be entered by said buttons upon a movement of the buttons toward the ends of the openings, buttoning members for performing buttoning operations with respect to the several buttons and buttonholes, and mechanism for operating the buttoning members to cause a plurality of buttoning operations to be performed substantially simultaneously.

74. A buttoning machine having, in combination, means for relatively positioning a plurality of buttons and a buttonhole fly with the buttons in edgewise relation to the buttonholes when the work is initially presented to the machine, and buttoning means constructed and arranged to move a plurality of buttons substantially simultaneously into the corresponding buttonholes in said edgewise relation and to tip the buttons into buttoned position.

75. A buttoning machine having, in combination, means for positioning a plurality of buttons to permit buttoning operations to be performed with respect to said buttons, buttoning instrumentalities arranged respectively for buttoning the different buttons, and means for operating said instrumentalities to cause different buttons to be buttoned in succession.

76. A buttoning machine having, in combination, means for relatively positioning a plurality of buttons and a buttonhole fly with the buttons in edgewise relation to the buttonholes when the work is initially presented to the machine, and means for effecting relative movement of said buttons and the buttonhole fly to cause a plurality of buttons to enter the buttonholes substantially simultaneously.

77. A buttoning machine having, in combination, means for relatively positioning a button piece and a buttonhole fly with portions of the button piece and the buttonhole fly where the buttons and the buttonholes are respectively located lying in planes transverse to each other, and means for effecting relative movement of the buttonhole fly and a plurality of buttons substantially simultaneously to button the work.

78. A buttoning machine having, in combination, button engaging means, mechanism for operating said means to button a plurality of buttons, and means for positioning the buttonhole fly for the buttoning operation comprising means manually movable into position to engage the fly adjacent to a plurality of buttonholes.

79. A buttoning machine having, in combination, button receiving means arranged to

position simultaneously a plurality of buttons attached to a button piece, and means for positioning a buttonhole fly for the buttoning operation comprising a member arranged to extend lengthwise of the edge of said fly along the series of buttonholes.

80. A buttoning machine having, in combination, button engaging means, mechanism for operating said means to button a plurality of buttons, and members arranged to engage the buttonhole fly substantially at opposite sides of the series of buttonholes to support the fly against pressure of the buttons in the buttoning operation.

81. A buttoning machine having, in combination, means for relatively positioning a button and a buttonhole fly, and buttoning means constructed and arranged to effect relative movement of the button and the buttonhole fly to cause the button to enter the buttonhole edgewise and then to tip the button in the buttonhole and to move the button bodily in a direction substantially perpendicular to the plane of the buttonhole fly to cause the button to clear the edges of the buttonhole.

82. A buttoning machine having, in combination, means for relatively positioning a button and a buttonhole fly, and means for pushing the button into a buttonhole in said fly by engagement with a side of the button head remote from the buttonhole and for tipping the button in the buttonhole.

83. A buttoning machine having, in combination, buttonhole fly positioning means, and means for pushing a button into a buttonhole in said fly by engagement with a side of the button head remote from the buttonhole and for tipping the button during the buttoning operation.

84. A buttoning machine having, in combination, buttonhole fly positioning means, button guiding means arranged to present a button in edgewise relation to a buttonhole in said fly, and buttoning means constructed and arranged to coöperate with said guiding means to cause the button to enter the buttonhole and to be tipped to an upright buttoned position with respect to the buttonhole fly.

85. A buttoning machine having, in combination, button positioning means provided with an opening to receive a button, a member arranged to engage in a buttonhole to position the buttonhole across the end of said opening, and means for moving the button out of said opening and into the buttonhole.

86. A buttoning machine having, in combination, means for relatively positioning a button and a buttonhole fly with a buttonhole extending lengthwise in substantially perpendicular relation to the plane of the button head, and means for relatively

moving said button and buttonhole fly to cause the button to enter the buttonhole in said relation.

87. A buttoning machine having, in combination, means for relatively positioning a button and a buttonhole fly with the lengthwise dimension of a buttonhole extending in substantially perpendicular relation to the plane of a button head, and means for moving the button into the buttonhole while the parts of the work are in said relation.

88. A buttoning machine having, in combination, means providing a guideway for a button, means for positioning a buttonhole fly with a buttonhole extending lengthwise in substantially perpendicular relation to the plane of a button head in said guideway, and means for moving the button along said guideway and into the buttonhole.

89. A buttoning machine having, in combination, buttonhole fly positioning means, and means for pushing a button into a buttonhole in said fly by engagement with the peripheral surface of the head of the button.

90. A buttoning machine having, in combination, means for relatively positioning a button and a buttonhole fly with the plane of the button head transverse to the lengthwise dimension of a buttonhole, and means for pushing the button into the buttonhole.

91. In a buttoning machine, a button receiving fork, means for guiding a button into said fork, a member adjacent to the fork for engagement in a buttonhole to position a buttonhole fly relatively to the fork, and means for moving said guiding means to an inoperative position to permit said member to engage in a buttonhole.

92. In a buttoning machine, an upwardly directed button receiving fork, means arranged to form an extension of said fork for guiding a button into the fork, a member disposed at the back of the fork for engagement in a buttonhole to position a buttonhole fly relatively to the fork, and means for swinging said guiding means backwardly to permit the buttonhole fly to be positioned.

93. A buttoning machine having, in combination a button receiving fork and a plunger relatively arranged to permit a button to be positioned in said fork with the side of the button head adjacent to said plunger, means for positioning a buttonhole fly across the end of the fork, and means for operating the plunger to force the button into a buttonhole in said fly.

94. A buttoning machine having, in combination, a button receiving fork and a plunger relatively arranged to permit a button to be positioned in said fork with the button head adjacent to said plunger when the work

is initially presented to the machine, buttonhole fly positioning means, and means for operating said plunger to force the button into a buttonhole in said fly.

5 95. A buttoning machine having, in combination, means providing a guideway for a button, means for positioning a buttonhole fly across the end of said guideway with a buttonhole substantially in line with the 10 guideway when the work is initially presented to the machine, and means for moving the button along the guideway and into the buttonhole.

96. A buttoning machine having, in combination, means providing a guideway for a button, means for positioning a buttonhole fly across the end of said guideway with a buttonhole substantially in line with the 15 guideway, means for moving the button along the guideway and into the buttonhole, and means for engaging the buttonhole fly adjacent to the buttonhole substantially at opposite sides of the path of movement of the button to support it against the 20 pressure of the button.

97. In a buttoning machine, means providing a guideway for a button, and a member arranged with reference to said guideway for engagement in a buttonhole to position the buttonhole fly across the end of 25 said guideway when the work is initially presented to the machine.

98. In a buttoning machine, a button positioning fork, and a member extending 30 lengthwise of said fork and beyond the end of the fork for engagement in a buttonhole to position the buttonhole fly across the end of the fork.

99. A buttoning machine having, in combination, a button positioning fork, buttonhole fly positioning means arranged to position the fly across the end of said fork and including a member for engaging the fly at the opposite side of the fork from the 45 button head to hold the fly against the pressure of the button in the buttoning operation, and means for moving the button out of the fork and into a buttonhole in the fly and for tipping the button to cause the 50 button head to be advanced over the edge of said member.

100. A buttoning machine having, in combination, means providing a guideway for a button, a plunger arranged for movement 55 lengthwise of said guideway in engagement with the head of the button, means for positioning a buttonhole fly when the work is initially presented to the machine with a buttonhole in position to be entered by the 60 button, and means for operating the plunger to force the button into the buttonhole.

101. A buttoning machine having, in combination, buttonhole fly positioning means, and buttoning means comprising a plunger arranged to engage the peripheral surface 65 of the button head and movable lengthwise to force a button into a buttonhole in said fly.

102. A buttoning machine having, in combination, means for relatively positioning a 70 buttonhole fly and a button piece with portions of said fly and button piece where a buttonhole and a button are respectively located extending in substantially perpendicular relation to each other; and means for 75 relatively moving the buttonhole fly and the button to cause the button to enter the buttonhole while the parts of the work are in said relation.

103. A buttoning machine having, in combination, buttoning means movable to perform a buttoning operation, means for engaging the lateral surface of the buttonhole fly at opposite sides of the buttonhole, to hold said fly against the pressure of the button 80 during the buttoning operation, and means for moving said buttonhole fly engaging means to operative position prior to the operation of the buttoning means.

104. A buttoning machine having, in combination, a plurality of spaced guides arranged to receive a plurality of buttons attached to a button piece, means for positioning a buttonhole fly with the buttonholes in position to be entered by the buttons as the 95 buttons are moved along the guides, and means for moving the buttons along the guides and into the buttonholes, said button guides and buttonhole fly positioning means being relatively arranged to cause each button 100 as it moves along its guide to be presented in edgewise relation to the plane of the buttonhole fly about the buttonhole.

105. A buttoning machine having, in combination, a plurality of buttoning instrumentalities arranged for performing buttoning operations with respect to a plurality of buttons and buttonholes, and means for operating said instrumentalities in such order as to effect the buttoning of one of the buttons at a different time from the simultaneous buttoning of the two buttons positioned on opposite sides of said one button.

106. A buttoning machine having, in combination, a plurality of buttoning instrumentalities arranged in a series for buttoning respectively different buttons, and means for operating different instrumentalities of said series at different times.

In testimony whereof I have signed my 120 name to this specification.

LEWIS J. BAZZONI.
